(57) **CLAIM**

The ornamental design for a hanging support, as shown and
described.

DESCRIPTION

FIG. 1 is a perspective view of a hanging support showing
my new design, in a state of use;

FIG. 2 is a front view of the hanging support;

FIG. 3 is a side view of the hanging support;

FIG. 4 is a bottom left angled perspective view of the
hanging support;

FIG. 5 is a top left angled perspective view of the hanging
support;

FIG. 6 is a top view of the hanging support; and,

FIG. 7 is a rear view of the hanging support.

The broken lines in FIG. 1 depicting a garment are directed
to environment only that forms no part of the claimed
design. All other broken lines in the drawings are directed to
portions of the Hanging Support that form no part of the
claimed design.

1 Claim, 7 Drawing Sheets
